UNITED STATES PATENT OFFICE.

GEORGE BEUOY AND GEORGE H. LOSHBOUGH, OF CEDAR VALE, KANSAS.

CAPONIZING INSTRUMENT.

1,002,961.

Specification of Letters Patent. Patented Sept. 12, 1911.

Application filed January 16, 1911. Serial No. 602,891.

To all whom it may concern:

Be it known that we, GEORGE BEUOY and GEORGE H. LOSHBOUGH, citizens of the United States, residing at Cedar Vale, in 5 the county of Chautauqua and State of Kansas, have invented certain new and useful Improvements in Caponizing Instruments, of which the following is a specification, reference being had to the accompanying drawings.

Our invention relates to instruments for caponizing, and has for its object to provide an easily operated and efficient device for this purpose having the functions of 15 grasping the organs to be operated on and holding them firmly until the operation is performed.

With the foregoing and other objects in view, the invention consists in the details of 20 construction and in the arrangement and combination of parts whereby an instrument of this character is produced that will possess advantages in points of efficiency, durability, and is inexpensive of manufacture, and at the same time being simple in 25 construction and operation.

The invention consists in the novel features of construction hereinafter described, pointed out in the claims and illustrated in 30 the accompanying drawings, in which—

Figure 1 is a side elevation of our improved instrument; Fig. 2 is a top plan view; Figs. 3 and 4 are detail perspective 35 views of the parts comprising our invention.

In referring more particularly to the drawings the numerals 1 and 2 indicate two rods or lengths of wire of any suitable size and weight. These rods have one of their ends bent upon themselves to form suitable 40 handles 3 and 3'. Just below the handles the rods are both bent twice at obtuse angles as shown at 4 and 5 and having bends 6 and 6' and one of said rods being extended upon the opposite side of the other so as to 45 limit the movement of the ends of the rods. The rod 1 is then bent at right angles intermediate of its ends forming a pintle portion 7 for the rod 2 which is coiled upon the pintle 7 as shown at 8. The rods are then 50 bent slightly inwardly and oppositely disposed as shown at 9. The ends of the rods 1 and 2 are tapered down into a point 9', and then bent upon themselves to form grasping

members 10 and 10' which are oppositely disposed so that their edges abut when 55 brought together in the act of closing. The outside edges of the grasping members are beveled as shown at 11 and 11' so as not to pinch or take hold of the arteries or other blood vessels when grasping the organ to be 60 removed during the operation. In having the rods bent slightly inwardly at 9 it will enable the person who is to perform the 65 operation to have a clear view of the work, and it will also serve to strengthen the instrument.

To those familiar with caponizing the operation of the instrument on the fowl, will be readily understood. Hence it is sufficient to say only that the instrument is 70 used to grasp the organ to be operated upon and hold it firmly during the operation, and not injure any of the arteries or blood vessels surrounding the organ. In grasping the organ the members 10 are to pass entirely over 75 it and grasp the chord connected to the part, so as to permit of straightening out the chord that it may be severed some distance from the part itself, thereby avoiding any accidental mishaps which so often occur 80 where the chord is severed close to the part.

While we have shown and described the preferred form of our invention, we do not limit ourselves to its exact construction but desire to make such changes as fairly fall 85 within the scope thereof.

It is noted that various changes in the details of construction and in the proportions may be resorted to for successfully carrying our invention into practice without sacrificing 90 any of the features or departing from the scope thereof.

Having thus described the invention what is claimed is:—

1. A caponizing instrument comprising 95 two rods having suitable handles formed at one end thereof, a pintle portion formed on one of said rods, the other of said rods being coiled and mounted on said pintle, grasping members formed on the end of said 100 rods opposite said handles and said rods being bent slightly inwardly and oppositely disposed to limit the movement of the grasping members.

2. A caponizing instrument comprising 105 two rods having suitable handles formed at

one end thereof, one of said rods being bent at right angles intermediate of its ends to form a pintle, the other of said rods being coiled and mounted on said pintle, and 5 grasping members formed on the ends of said rods opposite said handles.

In testimony whereof we hereunto affix

our signatures in the presence of two witnesses.

GEORGE BEUOY.

GEORGE H. LOSHBOUGH.
